JOSEPH F. LAMB, OF NEW BRITAIN, CONNECTICUT, ASSIGNOR TO LANDERS, FRARY & CLARK, OF NEW BRITAIN, CONNECTICUT, A CORPORATION OF CONNECTICUT

SIGNAL DEVICE FOR INDICATING COOKING TEMPERATURES OF WAFFLE IRONS AND THE LIKE

Application filed December 18, 1928. Serial No. 326,794.

The aim of the present invention is to provide an improved, simplified and accurate arrangements for giving a visible signal when the grids of an electrically heated waffle iron or the like have reached that degree of heat which is necessary to properly cook the batter.

A further aim of the invention is to provide a signal device of this sort which is simple in construction, which may be readily assembled upon the waffle iron, which may be very easily and quickly adjusted to indicate that temperature of the iron which is most desirable for cooking, and which will accommodate itself to expansion and contraction of the parts under heat changes.

A still further aim of the invention is to provide a device of this sort which is readily understandable and which may be easily observed by the user of the iron.

Other objects will be in part obvious and in part pointed out more in detail hereinafter.

The invention accordingly consists in the features of construction, combination of elements and arrangement of parts which will be exemplified in the construction herein-after set forth and the scope of the application of which will be indicated in the appended claims.

In the accompanying drawings, wherein I have shown, for illustrative purposes, one of the many embodiments which the present invention may take:

Figure 1 is an elevational view showing, more or less diagrammatically and partly in broken lines, a waffle iron equipped with the signal device of the present invention, the shutter of the signal device being illustrated by dotted lines in the position which it assumes when the iron has been heated to the correct temperature;

Fig. 2 is a side elevational view of the signal device, so much of the waffle iron being shown, partly in section and partly in elevation, as is necessary to disclose the installation;

Fig. 3 is a top plan view of the signal device;

Fig. 4 is a front elevational view of that portion of the casing behind which the signal

device is located, the signal device being shown in dotted lines and in the position which it assumes when the waffle iron is cold; and

Fig. 5 is a view looking at the forward end 55 of the signal device.

Referring to the drawings in detail, the waffle iron therein disclosed is illustrated by way of example only. This waffle iron is shown more or less diagrammatically, as it is 60 obvious that the improvements of the present invention may be incorporated in waffle irons of various sizes and shapes, and the specific construction of the waffle iron forms no part of the present invention. The waffle iron is 65 shown as having a base 10 upon which is mounted the lower grid 11. The upper grid, designated by the numeral 12, is hinged in the usual manner so as to be swung into and out of position, this arrangement not being 70 illustrated as it is an old and well-known one. Carried on the top of the grid 12 is a heating unit which is enclosed by a casing 13. The top of the grid 12, the heating unit thereon and the signal device of the present invention 75 are all encased or housed in a top cover 14 which, as usual, is made of sheet metal pressed to the desired form. The top cover, in the present instance, has a cylindrical skirt portion which rests upon a flange or ledge 15 provided on the grid 12.

Referring now to the improvements of the present invention, there is located above the heating unit and within the top cover 14 a 85 thermostatic element which carries (preferably in an adjustable manner) a shutter which, when the iron is cold, is adapted to blank an opening in the skirt portion of the cover and which shutter, when the iron is hot, is moved by the thermostatic bar or member 90 away from the opening so that a fixed colored surface behind that opening is exposed to view, indicating that the iron has reached the desired degree of temperature. The opening in the top cover 14 is indicated by the numeral 25 and is preferably located at the front 95 of the iron.

Immediately behind the opening 25, and spaced rearwardly of that portion of the skirt 100 in which the opening 25 is located, is a fixed

surface 26 which is colored, such as red, so as to contrast with the color of the top casing and the shutter. This surface 26 may be provided on a generally U-shaped bracket 27 secured to the cylindrical wall of the casing 13.

The thermostatic member, in the present illustrative disclosure of the invention, is in the form of a straight strip 28 of thermostatic metal and, if desired, may be made of two strips of metal having different coefficients of expansion. One end of the thermostatic member 28 is secured to a bracket or angle-iron piece 29 which, in turn, is secured to the top of the casing 13 in such manner that the thermostatic member is generally disposed radially with respect to the waffle iron. The member, which is moved by the thermostatic bar in order to expose the colored surface and thus give a visible signal that the iron has reached the desired degree, is shown, by way of exemplification, as being in the form of a plate 30 positioned immediately behind the skirt portion of the top cover 14 and adapted to move circumferentially between that skirt portion and the colored surface of the bracket 27. This plate portion may be of any suitable shape or configuration but is shown, in the present instance, as having, at one side edge, a generally curved or semi-circular recess 31. The plate portion 30 is carried by an arm 32 which preferably is in the form of a strip integral with the plate 30. This arm extends upwardly from the upper edge of the plate 30 and then extends rearwardly. The arm, between its ends, is twisted on a longitudinal axis through substantially 90° in order to provide a portion 33, the width of which lies in a horizontal plane, and a portion 34, the width of which is vertically disposed for the purpose hereinafter described more in detail.

The arm 32 is connected to the thermostatic bar 28 for sliding or telescopic movement in order to permit the device to automatically adjust itself to variations in the dimensions of the parts when such parts are subjected to heat changes. This connection, in the present instance, consists in forming the rear end of the arm 32 with a guideway which slidably receives the free end of the thermostatic bar 28. More particularly, the arm is provided at its rear end and at its opposite side edges with wings 35 which are bent over laterally and then towards each other in order to provide a channel or guideway for the reception of the thermostatic member 28.

The operation of my improved mechanism will be readily understood from the foregoing description taken in connection with the accompanying drawing. When the iron is cold, the parts will be in the position illustrated in Figs. 2, 3 and 4 and in which position the shutter or plate 30 will blank the opening 25 so that the surface 26 is hidden from view. As the iron heats up, the thermo-

static member 28 will flex and will move the shutter 30 circumferentially, in the present instance to the right, referring to Fig. 4. When the shutter has thus been moved to a position where the plate 30 is entirely out of the range of the opening 25, that is, when the plate has reached the position shown in Fig. 1, the cook will now see, upon looking at the opening 25, a red spot defined by the edge of that opening and will, therefore, know that the iron has reached that degree of heat for which the mechanism has been set as the cooking temperature. It will thus be observed that the signal is easily understandable and can be very quickly read, for, so long as the hole 31 is totally or partially blanked by the shutter, the iron is known as not being hot enough for proper cooking and, as soon as the opening has been entirely uncovered, it is known that the iron has reached the desired degree of temperature.

As previously pointed out, the shutter is slidably mounted on the thermostatic bar, a feature which is of importance in that the shutter may be manually adjusted radially, and the shutter will automatically adjust itself in a radial direction should such automatic adjustment be necessary due to changes in dimensions in the parts of the waffle iron. Owing to its ability to self-adjust itself, the shutter will not unduly drag on the cover 14 or the bracket 27 in the event it should engage the same, and the parts may be made with relatively large tolerances, a feature of importance as, in articles of this sort, it is necessary to provide large tolerances for the sake of economy in manufacture. It will also be observed that the shutter or plate portion 30 may be adjusted vertically by merely bending the portion 33 of the arm 32. Furthermore, the plate portion may be adjusted laterally with respect to the thermostatic bar 28 by bending the portion 34 of the arm 32. In order to insure that the top cover is positioned upon the grid 12 in proper relation to the signal device, the front face of the plate 30 may have a circular score mark 36 of the same or very slightly smaller diameter than that of the hole or opening 25. In securing the cover in place, the cover is first positioned with the opening 25 concentric to the score mark, and then the screws or other fastening means for securing the cover in place are tightened up.

As many changes could be made in the above construction and many apparently widely different embodiments of this invention could be made without departing from the scope thereof; it is intended that all matter contained in the above description or shown in the accompanying drawing shall be interpreted as illustrative and not in a limiting sense.

It is also to be understood that the language used in the following claims is in-

tended to cover all of the generic and specific features of the invention herein described and all statements of the scope of the invention which, as a matter of language, 5 might be said to fall therebetween.

I claim as my invention:

1. A signal device for indicating cooking temperatures of waffle irons and the like, and comprising a thermostatic element, a 10 member adapted to be moved thereby, and a colored surface exposed to view when said thermostatic element has moved said member to a predetermined position, said member being slidably mounted on said thermostatic element.

2. A signal device for indicating cooking temperatures of waffle irons and the like, and comprising a thermostatic bar adapted to flex under heat changes, a member adapted 20 to be moved thereby, a colored surface adapted to be exposed to view when said thermostatic bar has moved said member to a predetermined position, and a connection between said member and thermostatic bar 25 permitting said member to move longitudinally of said bar, said connection comprising a sleeve-like portion connected to said member and slidably receiving said bar.

3. A signal device for indicating cooking 30 temperatures of waffle irons and the like, and comprising a thermostatic bar, a shutter adapted to be moved thereby, and an arm carrying said shutter and connected to said bar, said arm comprising a relatively thin 35 strip of metal twisted between its ends through substantially 90° to provide portions at right angles to one another adapted to be bent to adjust said shutter.

4. A signal device for indicating cooking 40 temperatures of waffle irons and the like, and comprising a thermostatic bar, a shutter adapted to be moved thereby, and an arm carrying said shutter and having longitudinal sliding movement on said bar, said arm 45 comprising a relatively thin strip of metal and having a portion, the width of which lies in one plane, and another portion, the width of which lies in a plane at right angles to the first plane.

5. In a signal device for indicating cooking 50 temperatures of waffle irons and the like and in combination, a grid, a heating unit thereon, a casing housing said unit and having a skirt portion provided with an opening, a surface behind said opening and adapted to be exposed to view when said opening is unblanked, a thermostatic bar within said casing and adapted to flex laterally, and a shutter slidably carried by said 55 bar and adapted to be moved thereby to and from position behind said opening.

6. In a signal device for indicating cooking 60 temperatures of waffle irons and the like and in combination, a grid, a heating unit mounted thereon and having a casing, a cover

housing said casing and provided with an opening in its circumferential wall, a colored surface behind said opening, a radially disposed thermostatic bar connected to the top of said casing, a shutter disposed between said opening and surface, and an arm carrying said shutter and slidably connected to said bar, said arm comprising a thin strip of metal having one portion, the width of which is horizontally disposed, and another portion, the width of which is vertically disposed.

7. In a signal device for indicating cooking temperatures of waffle irons and the like and in combination, a grid, a heating unit 70 thereon, a cover housing said heating unit and grid and having a skirt portion provided with an opening therein, a fixed member behind said opening having a colored surface, a thermostatic bar within said cover and arranged to flex in a plane parallel to the plane of said grid, and a shutter carried, and entirely supported by, said bar normally located between the portion of said skirt having said opening and said surface.
